No. 640,329.

Patented Jan. 2, 1900.

G. SCHULTZ.
WIRE FENCING MACHINE.

(Application filed Mar. 30, 1898.)

(No Model.)

UNITED STATES PATENT OFFICE.

GUSTAVE SCHULTZ, OF LITCHFIELD, MINNESOTA.

WIRE-FENCING MACHINE.

SPECIFICATION forming part of Letters Patent No. 640,329, dated January 2, 1900.

Application filed March 30, 1898. Serial No. 675,710. (No model.)

To all whom it may concern:

Be it known that I, GUSTAVE SCHULTZ, a citizen of the United States, residing at Litchfield, in the county of Meeker and State of Minnesota, have invented a new and useful 5 Wire-Fencing Machine, of which the following is a specification.

My invention relates to machines for laying, winding, and stretching line-wires, and 10 is especially intended for such work on fences of either barbed or plain wire.

The object of my invention is to furnish the farmer with a cheap, simple, durable, and efficient device in the form of a truck with 15 which he can unwind, lay out, and stretch wires in erecting wire fences and also wind up wires when taking down such fences.

With this object in view my invention consists in a machine for the purpose described 20 built in the form of a truck, with an axle, two wheels thereon, a tongue secured rigidly to the axle, an adjustable standard attached near the front end of the tongue, carrying a wheel to support the outer end of the tongue, 25 hooks at the forward end of the tongue to grasp in drawing the truck from place to place and to engage around a post when stretching the wire, two standards rising from the axle, near each end, connected at the top by a cross-bar and having downwardly and inwardly 30 inclined notches in their rear edges to receive the pintles or journals of a spool for wire, suitable winding mechanism, and means for holding the spool in the notches.

35 My invention further consists in the improved construction, arrangement, and combination of parts hereinafter fully described and afterward specifically pointed out in the appended claim.

40 In order to enable others skilled in the art to which my invention most nearly appertains to make and use the same, I will now proceed to describe its construction and operation, reference being had to the accompanying 45 drawings, forming part of this specification, in which—

Figure 1 is a perspective view illustrating a machine constructed in accordance with my invention in position for practical operation.

50 Fig. 2 is a rear end elevation of the same. Fig. 3 is a sectional view on the plane indicated by the broken line 3 3 of Fig. 2. Fig.

4 is a similar view on the plane indicated by the broken line 4 4 of Fig. 2. Fig. 5 is an enlarged view of the means for retaining the 55 pintles on the spool of wire in the bearing-notches.

Like letters of reference mark the same parts wherever they occur in the different figures of the drawings.

Referring to the drawings by letters, A indicates an axle, upon the ends of which are mounted wheels B B, and from which projects forward the tongue C, the tongue and axle being braced, as is usual, at D. The tongue 60 C is slotted near the front end to receive an upright rod E, provided with a series of perforations E', said rod being adjustably secured in position on the tongue by means of the screw E², passing through the tongue and 65 any desired perforation in the bar. The lower end of the bar E is forked and serves as a bearing for the wheel F, upon which the tongue is supported. Double-armed hooks G are secured in the outer end of the tongue 70 and serve for the double purpose of hand-holds in drawing the truck and of hooks to engage around fence-posts in the operation of stretching the wire. Uprights H H' are mounted on the axle A and connected together at their upper ends by a cross-bar H². In their rear edges these uprights H and H' 75 are provided with inwardly and downwardly inclined notches I and I', reaching to about the center of the uprights. These notches I 80 receive the pintles or journals J of a roller or spool K of wire. Upon one end of the spool is secured a ratchet-wheel L and at the other end a ratchet-wheel M, the teeth of the ratchet-wheels pointing in opposite directions, and pawls N and O, pivoted to the inside of the uprights, above the spool, engage 85 the teeth of these ratchet-wheels, the pawl N preventing the turning of the spool in a direction to wind up the wire and the pawl O 90 acting in the opposite direction to prevent unwinding, so that by engaging both pawls with their respective ratchet-wheels the spool 95 will be held against turning in either direction. The pawls N and O are provided with 100 weighted elbow-arms N' and O', which will hold the pawls either in or out of engagement, according as they are adjusted. In order to stretch the wire, one of the hooks G may be

engaged around a post, when by winding up the wire it may be stretched to any desired tension. The wire can be also stretched by pulling the truck when both pawls are engaged with the ratchet-wheels, as before described. To permit of winding wire on the spool, the pawl N is released, and to unwind the pawl O is released, a suitable crank-handle P being provided for turning the spool.

10 In order to counteract any tendency of the pintles of the spool to jump out of their bearing-notches, I have provided a latch or bolt Q, provided with a vertical slot Q', through which a screw R passes into the upright H, 15 the forward end Q² of the bolt passing downward across the notch when in its lowermost position, as shown in Figs. 4 and 5. A pin S in the upright prevents the bolt from being moved by the pintle when the bolt is locked, 20 as shown.

The construction and operation of my invention will be readily understood from the foregoing, and while I have illustrated and described what I now consider to be efficient 25 means for carrying out my invention, I do

not wish to be understood as restricting myself to the exact details of construction shown and described, but hold that such slight changes or variations as might suggest themselves to the ordinary mechanic would properly fall within the limit and scope of my invention. 30

Having thus fully described my invention, what I claim as new, and desire to secure by Letters Patent of the United States, is— 35

In a wire-fencing machine, the combination with uprights having downwardly-inclined notches, latches Q slidably mounted above said notches having downwardly-projecting fingers Q' lying adjacent to the notches, a winding-drum mounted in the said notches and carrying ratchet-wheels having oppositely-disposed teeth, and weighted pawls mounted on the uprights above the notches and adapted to engage the above-mentioned 40 ratchet-wheels, substantially as described. 45

GUSTAVE SCHULTZ.
